FIG. 3.

FIG. 1.

FIG. 2.

Inventor:

P. Mackay.

UNITED STATES PATENT OFFICE.

PAUL MUCHAJER, OF CHARLOTTENBURG, GERMANY, ASSIGNOR OF ONE-HALF TO
GUNDKA-WERK VEREINIGTE BLECHSPIELWARENFABRIKEN, OF BRANDENBURG
HAVEL, GERMANY.

TYPEWRITER.

Application filed June 18, 1923. Serial No. 646,131.

To all whom it may concern:

Be it known that I, PAUL MUCHAJER, a citizen of the German Republic, residing at Charlottenburg, Germany, have invented certain new and useful Improvements in Type-writers, of which the following is a specification.

This invention relates to a typewriter of the kind having a single key-lever whereby the carriage is moved and the types set and operated for printing.

The object of the invention is to produce a typewriter of a very simple construction, and the invention consists in the various details of such construction as hereinafter set forth and claimed. The operating lever, which is set relative to a type scale on the casing, is guided by a cam formed in the casing wall into the correct printing position. The spacing and shifting levers are mounted on the same shaft, and so are the rocking elements whereby the printing and shifting movements are imparted to the printing wheel. These features, in addition to others which will be hereinafter described, are combined to form a very simple and easily operated typewriter.

Fig. 1 of the accompanying drawings represents a plan of the machine, and

Fig. 2, a vertical section of the same.

Fig. 3 is a vertical section at right angles to Fig. 2, and

Fig. 4, a group of detail views of the type wheel fastening and of a modified form of ribbon holder.

The casing 1, which is drawn out of a single piece of metal, has a curved front. A type scale is provided on the top wall close to the front edge and behind it is a curved slot through which an index 6 projects. The index is connected by means of an upright 5 to an arm 3 which moves in a horizontal plane about a pivot 4 connected to a bracket 2, the latter being fixed to the back wall of the casing. The pivot 4 also holds a fork 19 which is connected by means of a stay bolt 20 to the arm 3 so as to move in unison with the latter for setting the type wheel 23 in conformity with the index 6. For this purpose the fork 19 engages a pin 18 which is secured to a toothed sector 16. This sector is pivoted at 17 to a rocking plate 11 which holds the bearing for the type wheel spindle 14. The plate 11 also guides a pinion 15 which meshes with the sector and which is

slidably feathered on the spindle 14 so that the latter will be rotated by the sector when the arm 3 is adjusted along the type scale. The rocking plate 11 is supported by means of upright arms 13 on a shaft 12 about which it rocks for applying the type wheel 23 to the platen 60. This operation is effected by means of a double-armed setting and printing lever 8 which is pivoted at 9 to a bracket on the arm 3 and which projects through a slot in the front wall 69 of the casing. The inner end 10 of the lever bears against and supports the rocking plate 11; the outer end is fitted with a key 68. The lever 8 is supported on the arm 3 so that it can be used for setting the latter before it is depressed for printing the set up type. In order to ensure correct printing position in all instances, the front wall 69 of the casing is formed with a comb between the teeth of which the lever 8 is admitted. The teeth of the comb are pointed so as to guide the lever into the correct printing position even if the setting should be faulty.

The type wheel is fitted with several rows of types. The upper row is normally in printing position, and the other rows can be brought into printing position by an axial adjustment of the spindle 14 which is supported by a fork 37 secured to the shaft 12. An arm 36 secured to the same shaft is pivotally connected to the shift lever 29 on which there are two keys 34 and 35. A depression of the key 34 turns the shaft 12 and raises the type wheel into position for printing from the second row of types. The stem 32 of the key 34 is loosely connected to the lever 29 so that the latter can move independently of the same for raising the type wheel into the third printing position. This adjustment is effected by means of the key 35 and its stem 33.

The pivot 27 which carries the shift lever 29 also carries the spacing lever 28. This lever is operated by the depression of the key 31 which is connected thereto by means of a stem 30. The lever 28 rocks a three-armed lever 39 which is pivoted at 38 to the rear wall of the casing. One arm of this lever is upright and carries a pawl 40 which is supported by a spring 41 tending to turn the pawl into engagement with a toothed rack formed on the paper carriage 45. When the lever 39 is rocked, in opposition to a spring 46, the pawl 40 strikes against a stop 43

which releases the pawl from the rack. Upon the release of the lever 39, the pawl re-engages the rack and advances the carriage through one tooth space as the lever 39 is restored by the spring 46 to the normal position. The stop 43 is formed on a bracket 44 which is secured to the casing. A spring 47, connected to the bracket 44, bears against the teeth of the carriage rack and rectifies in each instance the position of the carriage. The carriage is also advanced by the rocking plate 11 at each printing operation. For this purpose an arm 42, connected to the plate 11, acts, by means of a pivoted screw 42' and an adjustable collar 39', on the third arm of lever 39 so as to rock it in opposition to the spring 46.

The carriage 45 is guided by means of a rod 51 in a split tube 52 mounted on the casing 1. It is also supported by a roller 53 mounted on the bracket 44. There is a slot 54 in the carriage frame to receive the roller 53, and the slot is open at one end to allow the carriage to be removed from the machine. A stop in the form of a stud 48 is passed through the slot 54 and secured to the frame by means of a nut 50 so as to determine the starting position of the carriage by abutment against the bracket 44, the stop being adjusted along the slot to the desired position. At the open end of the slot 54 there is in the cheek plate of the frame a slot 49 through which the stop can be introduced and removed without a complete detachment of the nut 50. By this arrangement the removal of the carriage is facilitated.

The line spacing is determined by a spring 58 having a tooth 58 which bears against the end of the platen roller 60 and snaps into equidistant notches 59 made in the roller.

A paper guide is provided in the form of a curved blade spring 55. This spring is connected to the carriage frame and fitted at its free end with a roller 56 which bears against the platen.

The bearing bracket of the spindle 14 carries a bridge piece 64 on the ends of which the ink-ribbon reels 63 are mounted. The feeding of the ribbon is effected by means of one of two pawls 62 fitted at opposite ends of another bridge piece 61 which latter is carried by posts connected to the casing 1. The bridge piece 61 is longitudinally adjustable so that it can be shifted for engaging either pawl to the ratchet wheel of the respective ribbon reel, the other pawl being simultaneously disengaged. As the bridge piece 64 is rocked together with the plate 11 and as the pawls 62 remain stationary, the engaging pawl will cause the reels to be rotated.

This ribbon arrangement may be modified as shown in Fig. 4 according to which the cheek plates of the carriage frame 45 are fitted with teeth 65 onto which can be slipped

at each end of the platen, an ink-ribbon holder 66. The ribbon 67 is stretched in front of the platen by means of the holders 66 which are resilient so as to yield and allow the ribbon to be applied by the type 70 wheel to the platen.

The type wheel 23 is supported on the spindle 14 by a disc 21 and is prevented from rotary displacement relative to the latter by the engagement with a recess 22 in the wheel 75 of a stud connected to the disc. The wheel is secured to the spindle by means of a curved blade spring 24 having a central elongated slot 26. The upper end of the spindle is formed with an elongated head 80 25 which is able to pass through the slot 26 in one position of the spring 24 and to interlock with the spring when the latter is turned through 90°, as shown in Fig. 4. By this arrangement the type wheel can easily 85 be exchanged.

To operate the machine, the key 68 is first moved horizontally until the index 6 registers with the sign to be printed and is then depressed for effecting the printing, one of 90 the shift keys 34, 35 being depressed in advance in case of need.

I claim:—

1. A typewriter of the character described comprising a casing provided with a type scale, an arm pivoted to the casing so that it can be adjusted in a horizontal plane, an index connected to said arm so that it can be set by means of the latter relative to the type scale, an operating lever pivoted to the 95 arm so that it can move relative to the latter in a vertical plane and so that it can be used for setting the arm, a rocking plate arranged in said casing and supported by the operating lever so that it can be rocked by means of 100 the latter, an axially and rotatably adjustable type wheel spindle carried by said plate so that it can be rocked thereby for printing, a toothed sector pivoted to said plate, a stay-bolt connecting the sector with said arm so 105 as to transmit motion from one to the other, a pinion feathered on the spindle and meshing with the sector so as to communicate rotation to the type wheel when the arm is adjusted, a comb formed in the casing wall 110 so as to receive the operating lever between its teeth and correct the setting when the lever is depressed for printing, a pivot pin, a shift lever arranged on said pin, means connecting the type wheel spindle with said 115 shift lever so that it can be axially adjusted thereby, a paper carriage, a spacing device for moving said carriage, connection between the rocking plate and the spacing device for operating the latter, a spacing lever arranged on said pivot pin, and connection between the spacing lever and the spacing device for 120 operating the latter.

2. A typewriter of the character described, comprising a casing which is drawn 125

- out of a single piece of metal and provided with a type scale, an arm pivoted to the casing so that it can be adjusted in a horizontal plane, an index connected to said arm 5 so that it can be set by means of the latter relative to the type scale, an operating lever pivoted to the arm so that it can move relative to the latter in a vertical plane and so that it can be used for setting the arm, a 10 rocking plate arranged in said casing and supported by the operating lever so that it can be rocked by means of the latter, an axially and rotatably adjustable type wheel spindle carried by said plate so that it can be rocked 55 thereby for printing, a toothed sector pivoted to said plate, means connecting the sector with said arm so as to transmit motion from one to the other, a pinion meshing with the sector and mounted on the spindle 60 so as to communicate rotation to the type wheel when the arm is adjusted, means for correcting the setting of the arm automatically when the operating lever is depressed 65 for printing, a pivot pin, a shift lever mounted on said pin and coupled to said shaft for rocking the same, a fork connected to said shaft and to the type wheel spindle so as to adjust the latter axially when the shaft is rocked, a paper carriage, a spacing 70 device for moving said carriage, connection between the rocking plate and the spacing device for operating the latter, and a lever mounted on said pivot pin and connected to the spacing device for operating the latter. 75
4. In a typewriter of the character described, a drawn metal casing, a split tube supported by said casing, a paper carriage comprising a frame and a rod adapted to guide the frame in said tube, the carriage 80 frame being provided with a longitudinal slot, a bracket connected to the casing, a roller mounted on said bracket and engaging the slot of the carriage frame for supporting the same, and a stud adapted to 85 be adjusted along said slot and to be secured detachably to the frame for limiting the movement of the carriage by abutment against said bracket.
5. In a typewriter of the character described, a type wheel spindle having an elongated head, a disc arranged on said spindle as a support for the type wheel, and a spring having an elongated slot 90 adapted to pass over said head in one position and to interlock with the same in another position of angular adjustment, the spring being adapted to hold the type wheel 95 in position on the spindle when engaged by the spindle head.
- 40 3. A typewriter of the character described, comprising a casing provided with a type scale, an arm pivoted to the casing so that it can be adjusted in a horizontal plane, an index connected to said arm so that it can be set by means of the latter relative to the scale, an operating lever pivoted to the arm so that it can move relative to the latter in a vertical plane and so that it can be used for setting the arm, a shaft 45 mounted in the casing, a rocking plate arranged loosely on said shaft and supported

PAUL MUCHAJER.
